STRAP FOR SKATES AND THE LIKE

Gerald R. Zeek, Westminster, Mass., assignor to Brunswick Sports Products Company, Torrington, Conn., a corporation of Delaware

Filed July 10, 1959, Ser. No. 56,719

Term of patent 14 years

(Cl. D34—14)

Fig. 1 is a top plan view of a strap for skates and the like, embodying my new design;

Fig. 2 is a side elevational view thereof;

Fig. 3 is a bottom plan view thereof; and

Fig. 4 is an enlarged fragmentary perspective view of the end of the strap.

The strap in Figs. 1, 2, and 3 has been broken away to indicate indefinite length.

I claim:

The ornamental design for a strap for skates or the like, as shown and described.
